TRANSMITTER

Harold D. Albrecht, Pennsauken, N. J., assignor to
 Radio Corporation of America, a corporation of
 Delaware

Application October 29, 1938, Serial No. 237,637

5 Claims. (Cl. 250—17)

My invention relates to vacuum tube coupling systems, and more particularly to modulation circuits in a transmitting system and inverse feedback circuits.

5 In transmitting systems and amplifiers employing degenerative or inverse feedback circuits for reducing distortion and hum, considerable difficulty has been experienced from phase shift in the feedback loop, particularly in cases where 10 audiofrequency transformers have been used in the circuit. It has been common practice to employ a conventional push-pull transformer consisting of a split primary and a closely coupled secondary for coupling from a push-pull or class 15 B high powered modulation amplifier to an R. F. amplifier anode circuit in a radio transmitter, for modulating the R. F. carrier in accordance with impressed audiofrequency signal waves. This transformer has prevented realizing the full 20 benefits of feedback in the reduction of distortion and hum, although in some cases special phase correcting networks have been added for the purpose of reducing the phase shift.

It is, accordingly, an object of my invention to 25 provide, in a transmitting system, improved coupling means free from phase shift, for coupling a modulator to an R. F. amplifier or relay employing degenerative feedback in the system.

It is a further object of my invention to provide 30 an improved circuit arrangement for coupling a double ended or divided output amplifier or relay into a single ended circuit.

It is a still further object of my invention to provide, in an amplifier system having degenerative 35 feedback, a simplified inductive coupling means with greatly reduced phase shift for coupling a double ended or divided output amplifier to a single ended circuit.

The novel features that I consider characteristic 40 of my invention are set forth with particularity in the appended claims. The invention itself, however, both as to its organization and its method of operation, together with further objects and advantages thereof, will best be understood 45 stood by reference to the following description of a specific embodiment, taken with the accompanying drawing, in which the single figure is a diagrammatic view of a radio transmitting system embodying my invention.

50 Referring to the drawing, I have shown schematically an oscillator 1, an R. F. amplifier 3, both in block diagram, coupled to the input of a push-pull R. F. amplifier stage 5, which in turn is coupled in push-pull to a final high powered 55 push-pull R. F. amplifier 7. The amplifier tubes

include the usual filament 2, grid 4 and anode 6. The output of amplifier 7 is coupled through transformer 9 to the antenna 11. The amplifiers 5 and 7 are coupled by means of a variably tuned circuit 13 including a split tuning capacitor 15 and center-tap R. F. inductance coil 17.

The R. F. amplifier 5 is modulated by means of a class B amplifier stage 19, in accordance with the teachings of Barton Patent 2,063,290 and includes tubes 21—21 and 23—23 arranged in parallel "push-push" relation respectively. The outputs of tubes 21 and 23 are connected to a center tapped iron core choke coil 25 in balanced relation. In effect, coil 25 is an auto transformer, the two halves being closely coupled so that the 15 voltage across one half is practically the same as that across the other half, although 180° out of phase. One end terminal of coil 25 is connected, through a stopping capacitor 27, e. g., of the order of 8 mfd., to a modulating reactor 29 at its 20 high potential end, preferably no magnetic coupling existing between the reactor and the coil 25.

The reactor is connected in the usual manner for plate modulation, between the high voltage 25 anode supply source 31 and the anodes or plates 6 of push-pull tubes 5, through an R. F. choke 33 and resistor 35, to a center tapped terminal on the coil 17. It will be noted that this terminal on coil 17 is at ground potential for the R. F., and 30 that this point is varied at audio potential with respect to ground, by means of the modulator.

The anodes of tubes 5 are effectively in parallel 35 so far as the impressed audiofrequency is concerned, and for this reason are considered to be a single ended circuit into which the divided output of the modulator 19 feeds. It is within the scope of my invention to employ my auto transformer to couple the output from a push pull audioamplifier into the grid circuit of a conventional single ended audioamplifier. I am well aware of the fact that an auto transformer connection of somewhat similar nature has been employed heretofore in feeding from a single ended output stage into a push-pull stage, as shown and 40 claimed by Davis Patent 2,032,921, but I am not aware of any prior arrangement for coupling in a reverse manner with resulting improvements, and more particularly in an inverse feedback combination, in accordance with my invention. 45 It is also within the scope of my invention to employ the arrangement of the Davis patent in a feedback loop circuit for reduction of phase shift. 50

In the system shown, which has been built and 55 used in accordance with my invention, the am-

plifier 19 is of the class B type, operated with grid bias, as disclosed in patent of Loughren 1,699,110, although other types of amplifiers, e. g., class A and class AB, could be employed in accordance with my invention. The tubes 21 and 23 were of the low impedance type, but were provided with sufficient negative grid bias so as not to be driven to draw grid current during normal operation, although an amplifier in which grid current is drawn could be employed; for example, as shown in Barton Patents 2,084,180 and 2,084,181. The amplifier 5 as actually used, was a class C type, although here again other types could be employed.

15 Ahead of power amplifier stage 19 is an audio-amplifier, shown in block diagram at 37. For the purpose of providing inverse or negative feedback, a portion of the final output energy existing in transformer 9 is taken, by means of a coupling coil 39, and fed back, through a rectifier circuit 41 into the A. F. amplifier 37, in accordance with the teachings of DeWitt Patent 2,093,751.

20 While I have illustrated my invention in connection with this type of feedback circuit, it also has advantages when used in a feedback involving the audio amplifier only, for example, as illustrated in Oman application, Serial No. 153,574, filed July 14, 1937 (same assignee). It 25 will be observed that in the Oman application the output audio frequency transformer is not included in the feedback loop. My invention will permit the inclusion of the output coupling means in the feedback loop by virtue of the reduced phase shift.

25 Besides eliminating the transformer, and the corresponding difficulties caused by phase shift, I have found that the use of a choke coil is substantially less expensive and simplifies design. 30 My improvement was applied in a given case to an existing transmitter, in use in a broadcasting station, and it was found that the phase shift was reduced to such an extent that the distortion in the transmitter, at 7500 cycles, was reduced to 35 approximately half of its former value. In making this change, I disconnected the secondary of the existing audio transformer of the system, using the primary as a choke coil, and added a modulating reactor in the manner shown at 29 40 in the present drawing.

45 Although I have illustrated but one embodiment of my invention, other modifications will be apparent from the disclosure to those skilled in the art. My invention, therefore, is not to 50 be limited except insofar as is necessitated by the prior art and by the spirit of the following claims.

55 I claim as my invention:

1. A transmitting system comprising a radio

frequency amplifier characterized by a double ended output circuit balanced for radio frequency currents, an audio modulation amplifier having output electrodes connected in a double ended output circuit, a reactor connected to said electrodes and constituting an auto-transformer for coupling said audio output circuit to said radio frequency amplifier output circuit in single ended relation for audio frequency modulation, and a degenerative feedback loop circuit in said system including said auto transformer.

2. In a transmitting system, a radio frequency amplifier, a double ended output audio amplifier, said amplifiers including thermionic tubes having cathodes, control electrodes and output electrodes, a power supply circuit for said output electrodes, means for coupling said audio amplifier to the radio frequency amplifier in single ended relation comprising a choke coil connected in balanced relation to the output electrodes of said audio frequency amplifier, a modulating reactor and stopping capacitor, and a coupling connection through said stopping capacitor to a point on said modulating reactor, said reactor being connected in the output electrode power supply circuit to said radio frequency amplifier, and said choke coil and reactor being characterized by absence of magnetic coupling, whereby phase shift is reduced.

3. The invention as set forth in the next preceding claim, wherein a degenerative feedback circuit is connected from the output of said radio frequency amplifier to the input of said audio amplifier.

4. In a transmitting system, a radio frequency amplifier connected to a source of radio frequency current, a double ended audio frequency amplifier connected to a source of audio frequency current and comprising a pair of thermionic devices connected in balanced relation, 40 said devices having output electrodes, a power supply circuit connected to said radio-frequency amplifier, an audio frequency reactor having end terminals connected respectively to said output electrodes, means for connecting a portion of said 45 reactor to said power supply circuit in such manner that said reactor constitutes an auto transformer for modulating said radio frequency amplifier with audio frequency current in said reactor, and an inverse feedback circuit connected from the output of said radio frequency amplifier to the input of said audio frequency amplifier and forming therewith a feedback loop including therein said reactor.

5. The invention as set forth in claim 4 wherein said audio frequency amplifier is of the class B type.

HAROLD D. ALBRECHT.
